UNITED STATES PATENT OFFICE.

WILLIAM F. DURYEA AND MOSES H. DURYEA, OF HACKENSACK,
NEW JERSEY.

PEN-RACK.

No. 826,233.

Specification of Letters Patent.

Patented July 17, 1906.

Application filed September 23, 1905. Serial No. 279,830.

To all whom it may concern:

Be it known that we, WILLIAM F. DURYEA and MOSES H. DURYEA, citizens of the United States, residing at Hackensack, in the county 5 of Bergen and State of New Jersey, have invented certain new and useful Improvements in Pen-Racks, of which the following is a specification.

Our invention relates to racks for holding 10 penholders, pencils, and other like articles, and more particularly to a rack which is adapted to be attached to the pigeonhole-partitions usually arranged above a desk.

The object of our invention is to provide a 15 very simple form of rack which shall hold the penholders or pencils above the top of the desk in a space which is ordinarily unoccupied, which will accommodate and hold any size of penholder or pencil, which is readily 20 attachable or detachable to or from the desk, and which is attractive and neat in its general appearance or design.

To this end our invention consists in the 25 general construction of pen-racks and details hereinafter described, and more definitely stated in the claims.

In the drawings, Figure 1 is a front view of the upper part of a desk, showing our invention applied to the pigeonholes thereof. Fig. 30 2 is a front elevation of the rack itself, about full size. Fig. 3 is a cross-section on line xx , Fig. 2.

Like numerals designate like parts in the several figures.

35 Our improved rack consists of an open frame having stretched across it at regular distances apart a number of flexible resilient cords between which the penholder or pencil is to be inserted. In the drawings, 2 indicates such a frame, preferably in the form of a 40 long rectangle, the space inclosed by the frame being divided into two parts by a central web 2'. This frame and the central solid portion or web may be made in as many 45 parts as desired or of one piece of wood, metal, or composition. The main function of the central web is to provide a bearing for the shaft 4 of a clamp; but it might be dispensed with if another form of clamp were used.

50 The upper and lower edges of the frame 2 are longitudinally grooved, as at 2", Fig. 3, to carry and protect that portion of the elastic cord 3 which projects above and below the frame. The elastic cord is threaded

through holes extending from the grooves 2" 55 into the inclosed space of the frame. The divisions of the pen-rack might be made by using short lengths of elastic cord, each stretched vertically between the upper and lower bars of the frame; but we prefer as 60 more practical to make the divisions by the use of a continuous length of cord fastened at one end, as at 3', in any suitable manner, carried along the groove 2" of one bar, passed upwardly through the bar and across the 65 opening of the rack to and through the other bar, then along the groove 2" for a short distance, approximately slightly shorter than the diameter of a penholder, to be again threaded downwardly through the upper bar 70 to and through the lower. This back and forth threading of the cord 3 is continued along the whole length of the rack, the end of the cord being made fast to the rack in any 75 convenient way.

While we may use a cord made of any elastic material and of any construction, we preferably use as best adapted to the purpose a cord composed of fine coiled wire—such as used for certain piano-strings. This is 80 resilient, does not corrode or decay, as would rubber, it is very flexible while retaining its elasticity, and so may be easily threaded through the holes of the frame, yields readily to the insertion of a penholder, and the slight 85 expansion of the coils acts to give a firmer grip upon the holder. It is superior to ordinary wire in that it is much more elastic and yielding and being flexible conforms to the shape of any pen or pencil, and yet does not 90 weaken as cord would.

In order to attach the rack to a desk, we provide it with a clamp which is adapted to grip one of the horizontal partitions of a desk in the position shown in Fig. 1. The clamp 95 which we consider best adapted to the purpose consists of a vertical rod 4, passing through the central web 2' in front of the grooves 2". This rod is bent rearwardly, as at 4', and is screw-threaded at its lower end 100 and carries a finger-nut 4". In putting this rack in place the partition of the desk is inserted between the bend 4' and the adjacent face of the upper bar of the frame. The finger-nut is then turned until the rack is firmly 105 clamped in place. It will be noticed that we show the upper face of the upper portion of the frame as cut down at the rear behind the

groove 2". This is done so that the projecting front portion 2" may form a stop to take against the front edge of the partition and prevent it turning about the clamp-bar 4 as a center. Any other form of stop may be used, however, or it may be omitted altogether, if desired.

One of the objections to all racks at present known to us is that they rest upon the top of the desk in a position where the penholders and pencils are most liable to get knocked off, misplaced, and distributed over the desk. Such racks also take up more room and are likely to get covered with papers. A pen 15 wet with ink and laid down on such a rack is likely, too, to come in contact with the papers on the desk and to soil them. These disadvantages are obviated by our device. It is located above the table-top of the desk, 20 and it holds the pens and pencils in a space heretofore unused. It may be made of any size to accommodate any number of implements and yet not obstruct the desk. The pens and pencils supported therein are not 25 likely to get knocked off or to come into contact with any papers. The pens may be easily inserted and withdrawn, and they are held securely. Another important point is that the elastic cord adapts itself to the gripping of any sized penholder or pencil. This 30 is not the case where corrugated bands of metal are used.

We do not wish to be limited to the exact details shown, as there are a number of 35 changes which might be made without departure from our invention. The shape of the frame might be changed and the number of clamps or their form varied. The finger-nut need not be mounted on the lower end of 40 the rod 4 before the frame, but anywhere along the said rod between the upper and lower bars of the frame or in a recess in the central web 2.

Having described our invention, what we 45 claim is—

1. A pen-rack comprising an inclosing frame having substantially parallel longitudinal bars, and elastic cords stretched across the opening of said frame from one bar to the 50 other adjacent to each other and capable of holding a pen or pencil between them, substantially as described.

2. A pen-rack comprising an inclosing frame having substantially parallel longitudinal bars, and elastic cords stretched across the opening of said frame from one bar to the other adjacent to each other and capable of holding a pen or pencil between them, in combination with a clamp for supporting it from 55 a desk structure, substantially as described.

3. A pen-rack, comprising a depending longitudinal frame inclosing a central opening, elastic cords vertically stretched across the opening of said frame adjacent to each other 60 and capable of holding a pen or pencil be-

tween them, and a clamp on the upper edge of the frame adapted to engage with a horizontal partition above the desk-table, substantially as described.

4. A pen-rack comprising an inclosing 70 frame, and flexible cords of coiled wire stretched across the opening of said frame adjacent to each other and capable of holding a pen or pencil between them, substantially as described.

5. A pen-rack comprising an inclosing frame, having upper and lower substantially parallel longitudinal bars and end bars, and flexible cords of coiled wire stretched across the opening of said frame adjacent to each 80 other from one longitudinal bar to the other and capable of holding a pen or pencil between them, substantially as described.

6. A pen-rack comprising a longitudinal frame formed of upper and lower bars inclosing a central opening, said bars having grooves along the outside edges thereof, an elastic cord threaded backward and forward through the said upper and lower bars and across the opening inclosed by the frame, 85 said cord being carried in the grooves referred to, and a clamp attached to the frame and adapted to engage with the desk structure, substantially as described.

7. A pen-rack comprising a longitudinal 90 frame having upper and lower bars inclosing a central opening, said bars being grooved along their outside edges, an elastic cord threaded backward and forward through the said bars and across the opening between 95 them, said cord being carried in the grooves of the said bars, a central web or post between the upper and lower bars, a screw-threaded rod passing vertically through said post and having an angularly-bent end, and a nut on 100 the lower end of said rod, substantially as described.

8. A pen-rack, comprising a longitudinal frame inclosing a central opening and having upper and lower bars, vertically-stretched 105 elastic cords extending from one bar to the other across said opening to form pen-holding divisions, and a clamp on said frame, adapted to engage with a desk structure, substantially as described.

9. A pen-rack, having a series of vertical pen-holding supports arranged in line, an upper longitudinal supporting-bar, and a desk-partition clamp above the said bar and thus adapted to hold the pen-rack in a dependent 110 position, substantially as described.

In testimony whereof we have signed our names to this specification, in the presence of two subscribing witnesses, this 18th day of September, 1905.
